(57) **CLAIM**

The ornamental design for a triple stack button earring, as shown and described.

DESCRIPTION

FIG. 1 is a perspective view of a triple stack button earring; FIG. 2 is a perspective top view of the triple stack button earring;

FIG. 3 is a front elevational view of a triple stack button earring; the rear elevational view being a mirror image thereof;

FIG. 4 is a right side elevational view of a triple stack button earring; the left side elevational view being a mirror image thereof;

FIG. 5 is a top plan view of the triple stack button earring; and, FIG. 6 is a cross sectional view of the triple stack button earring taken along line 6-6 in FIG. 5.

The broken line rendering of an ear and earring back represent environmental matter and form no part of the claimed design.

1 Claim, 3 Drawing Sheets
